UNITED STATES PATENT OFFICE.

WILLIAM L. MCADAMS, OF COQUILLE, OREGON

MAGNETIC ORE SEPARATOR

Application filed March 16, 1926. Serial No. 95,055

The present invention relates to a machine or apparatus for separating ores from sand and gravel, and aims to provide a novel and improved device of this character in which magnetic force or attraction is utilized to cause the ores to be drawn from the sand and gravel, said device being so constructed that after the ores are separated from the sand and gravel they are conveyed to a point where the magnetic power is broken, at which time said ores are deposited into a hopper.

Another object of the invention is the provision of a rotatable disk constructed of a series of spaced sections, said disk being arranged above a trough in which the unseparated substances are deposited and has arranged thereabove an electric magnet which magnetizes the spaced plates as they pass therebeneath and over the trough, said plates remaining magnetized until they move to one side of the trough, at which time the magnetic power is broken and the ores conveyed by the plates will be deposited in the hopper.

A further object of the invention is to provide a sectional disk having a sheet of glass or other similar material arranged on its under surface for preventing direct contact of ores with the plates of the disk in order to effect the efficient dropping of the ores as the plates will also remain slightly magnetized due to their contacting with the electric magnet.

It is also an object of the invention to provide a device of the above indicated character, which is substantial in construction, which can be manufactured for a nominal sum, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a longitudinal section through my improved apparatus,

Figure 2 is a top plan thereof,

Figure 3 is a cross section taken on line 3-3 of Figure 2, and

Figure 4 is a fragmentary section showing the lower portion of the electric magnet and

one of the plates of the disk in contact with said magnet.

In carrying out the invention, the numeral 10 designates a trough, which is slightly inclined. The trough at its upper end 11 where the unseparated substances are deposited is relatively narrow and has its side walls gradually flared outwardly, as at 12. At the point where the side walls of the trough are flared outwardly, a series of strips 13 are attached to the bottom wall of the trough so as to cause the substances deposited in the trough 11 to be directed toward the sides of the trough 10 and over its entire area. The trough after being flared out at 12 remains substantially the same width throughout the remainder of its length, as at 14. Adjacent the strips 13 on the portion 14 of the trough, I arrange a series of angularly disposed strips 15 for directing the substances towards one side wall of the trough. At the end of the trough opposite to that where the substances are deposited thereon is a series of ribs 16 extending across the trough on the bottom wall thereof so as to form ripples in the water passing thereover so that the heavier particles of the substance will engage between said ribs and be retained there due to their weight.

Secured to one side wall of the trough 85
10 at the portion 14 between the ribs 15
and 16 is a bearing 17 for rotatably receiving
90 a shaft 18 which has mounted on its
upper end a disk 19. The disk 19 is of relatively
large size so that a portion thereof always
extends over and above the trough,
as clearly shown in Figures 2 and 3 of the
drawings. The disk 19 is constructed of
three metallic plates 20 slightly spaced from
each other, as at 21, at certain edges thereof
so as not to contact with one another.
Arranged below the metallic plates 20 and
supporting the same is a plate 22 constructed
of glass or other similar material which is
non-conductive, the purpose of which will
be set forth as the description proceeds. 95 100

Attached to the opposite side of the portion 14 of the trough from that where the disk is rotatably mounted is a bracket 23 which extends over the trough and supports an electric magnet 24 centrally of the trough. The electric magnet 24 has arranged thereon centrally thereof a depending socket 25 which is square in cross section for slidably receiving an upstanding lug 26 of similar 110

shape in cross section. The lug 26 is arranged upon the upper surface of an arcuate shaped shoe 27, and is secured thereto, as at 28. The arcuate shoe 27 is adapted to engage two of the metallic plates of the disk at one time as the disk 19 is rotated. It can be seen that when a circuit is completed to the electric magnet the shoe 27 will transmit the magnetic power to the plates 20 in engagement therewith so that certain ores contained in the substance deposited in the trough will be drawn upwardly into contact with the glass plate arranged upon the lower portion of the disk. As the disk rotates and the plates 20 disengage the shoe 27, the magnetic power to said plates is broken. Consequently all ores attracted by the plates will drop therefrom. It is to be noted by referring to Figures 2 and 3 of the drawings, 20 that when a plate 20 is out of engagement with the shoe 27 said plate is to one side of the trough and positioned over a hopper or chute 29, into which the ores attracted by the plate are deposited. The chute or hopper 29 25 opens into a box or receptacle 30 positioned upon the floor.

Mounted beneath the trough 10 is an electric motor 31 having a small pinion 32 on the drive shaft thereof which meshes with a gear 33. The gear 33 is mounted upon one end of a shaft which has arranged on its opposite end a sprocket gear 34 over which a sprocket chain 35 is trained and which also is trained over a large sprocket gear 36. 35 The gear 36 is mounted upon one end of a shaft 37 which has its opposite end slidably received in the lower end of the rotatable shaft 18. The shaft 37 is feathered to the shaft 18 so that a driving connection between 40 said shafts is at all times completed. Arranged upon the lower end of the shaft 18 is a pair of spaced collars 38 which are engaged by lugs 39 arranged upon the ends of a yoke lever 40. The yoke lever 40 is pivotally connected, as at 41, to a segment 42 and has arranged thereon a pawl 43 for engaging the segment 42 in order to hold the lever in adjusted position. It can be seen that by swinging the lever 40 on its pivot 41, that the 45 shaft 18 is either moved upwardly or downwardly, thus changing the relative distance of the plates 20 from the portion 14 of the trough. By providing this adjustment for changing the relationship of the plates from the trough, it can be seen that the magnetic power or drawing power of the plates may be changed according to the substances deposited in the trough.

By providing the glass plate on the under 50 surface of the disk 19, all ores attracted by the plates 20 are prevented from contacting directly with the plates, thus eliminating the liability of the ores remaining attracted by the plates after the plates have disengaged 55 the shoe, due to the fact that said plates may

become slightly magnetized due to contacting with the shoe 27. Furthermore, the provision of a glass plate will eliminate the danger of the plates 20 becoming rusted or corroded by the water or liquid contained in the substance deposited in the trough.

In operation, the substances to be separated are deposited at the narrow portion of the trough 10 with a sufficient quantity of water. The water will tend to wash the substances downwardly in the trough and when the same come in engagement with the strips 13 they spread over the entire width of the enlarged portion 14 of the trough. When first engaging the enlarged portion 14 of the trough, the substances in the water are directed, by means of the strips 15, towards the edge of the disk 19. When the substances and water pass under the disk arranged over the trough and which are in contact with the shoe 27, the ores contained in the substance will be attracted by the magnetic power transmitted to the plates 20 contacting with the shoe, due to the magnet 24 being energized. By the positioning of the magnet directly over the trough, the magnetic fields or drawing powers of the magnet will also be in an upward direction, thus aiding the plates in raising or drawing the ores to engagement with the glass plate arranged thereunder. The disk 19 is timed so as to revolve very slowly, substantially eight to fifteen revolutions per minute, which will permit a sufficient amount of ore to be drawn up and attracted to the under surface of the glass plate. When a plate 20 which has been positioned over the trough turns until the shoe 27 is out of engagement therewith, the same is arranged over a hopper or chute 29 so that as soon as the magnetic power of the plate is broken, the ores attracted by the plate will be deposited in the hopper or chute 29. After a plate 20 has deposited the ores attracted thereby, the same gradually moves until it is again engaged by the shoe so as to again have magnetic power transmitted thereto.

From the foregoing, it can be seen that my improved apparatus is continuous in operation, and need not be stopped in order to supply a new quantity or unseparated quantity of substance thereto, and will separate the substances as the same pass beneath the disk. By providing the adjustment of the disk towards or away from the trough, the magnetic powers of the plates may be varied according to the quantity or quality of the ores contained in the sand and gravel or other substance the device is to separate.

Having thus described my invention, what I claim as new is:

1. A magnetic ore separator comprising a trough having a passageway therethrough, a rotatable member journaled upon an axis located at one side of the trough, a magnet

disposed above the passageway through the trough and extending over that part of the rotatable member which is disposed above the trough, and the trough being provided at its bottom with diagonally disposed ribs adapted to direct material toward the peripheral portion of the rotatable member.

2. A magnetic ore separator comprising a trough, a rotatable member journaled upon an axis fixed at the side of the trough, said rotatable member being composed of an un-

derplate of insulating material, spaced magnetizable segments mounted upon the upper surface of said insulating material, each of said segments being of sufficient size to completely bridge the trough when disposed thereover, and a magnet located above the rotatable member and having a shoe adapted to contact with said segments.

In testimony whereof, I have affixed my signature.

WILLIAM L. McADAMS.
